POLISHING MACHINE

Gotthold Harry Meinzer, Glendale, Calif.

Application September 6, 1944, Serial No. 553,126

2 Claims. (Cl. 51—170)

1

This invention relates to portable apparatus for polishing, waxing, sanding or otherwise smoothing fixed solid surfaces such as floors, pavements and automobile bodies.

The portable polishing devices currently in use are of two general types, in which the element bearing on the surface to be polished takes the form respectively of a disc rotating about its own center and of an endless belt.

These devices have several disadvantages which limit their utility. As in both forms the actual polishing element must move at a relatively low speed, a long reducing gear train is required, causing the device to be mechanically inefficient. This low efficiency in turn requires the use of a relatively heavy motor, which reduces the portability of the machine and makes it cumbersome to handle. In neither of these forms is it practicable to construct a unit of such weight as may be held in the hand, as for example for automobile polishing.

Again, both of these forms have a strong tendency to eject the polishing agent (wax or abrasive) from the immediate area being treated, the disc type by moving it outwardly from the center of the disc, the belt type by moving it ahead of the belt, which necessarily travels toward the unpolished part of the surface.

These structural disadvantages result, in either form, in a machine of excessive weight and consequent limited portability, a machine which is subject to rapid depreciation, which is too costly to be available for general household use, and which cannot be constructed in such size and weight as to be applicable to other than horizontal plane surfaces.

The improvement over the above devices herein described lies basically in means for moving a non-rotating polishing element through a circular path of small radius, at high speed. This movement is produced by taking advantage of the inertia of a pair of relatively light weights affixed to the motor shaft and revolving with it, thus avoiding the necessity for speed reduction or power transmission of any kind. The improvement is evidenced in the production of a machine of relatively light weight, having a sharply reduced tendency to extrude the abrasive, of high efficiency and durability, and capable of being manufactured at a considerably reduced cost.

An illustrative embodiment of the invention is shown in the attached drawings, in which

Fig. 1 is a vertical section through the machine, the motor and actuating weights being in elevation;

Fig. 2 is a plan view of the assembly;

Fig. 3 is an outline elevation of the assembly illustrating attachments which increase its utility for polishing extended horizontal surfaces such as floors;

Fig. 4 is a diagram of the assembly illustrating the forces which produce vibratory movement of the polishing element in its own plane;

Fig. 5 is a force diagram illustrating the proportioning of certain elements of the device.

Referring first to Figs. 1 and 2, an electric motor 10 is provided with a skirt 11 or other means by which it is rigidly supported from a platen 12 with its shaft perpendicular to the plane of the outer face of the platen. This element should be rigid and of comparatively light weight: thus in small size it may be formed of plywood, hardwood or a light metal, or in larger sizes of wood with metallic reinforcement.

To the lower (outer) face of the platen is affixed a resilient pad 13 which may be of a carpet having a deep pile, of soft rubber or of sponge rubber. This soft pad is useful in floor waxing and polishing, a renewable cloth 14 being folded over its surface and retained by suitable means such as the spring-contracted ring 15.

To the motor shaft 16 are attached eccentric weights 17 and 18, these weights revolving with the armature of the motor and being at least substantially in phase. The relations of these unbalanced weights to the system as a whole will be described.

At opposite sides of the motor, brackets 19 and 20, attached to the motor or the skirt as may be convenient, carry resilient elements 21—21 to which the handle or guiding element is attached. These elements isolate the vibration of the system, prevent its transmission to the hand of the operator and avoid damping the vibration of the system by any laterally applied force used in moving the device over the work surface. They must be fully resilient: thick-walled, soft rubber tubes or closed coil springs are suitable for use in this position, the drawing illustrating rubber tubes maintained in tension between the brackets.

A convenient guiding element for small units, such as are suitable for polishing automobile bodies and other curved or vertical surfaces, is shown in Fig. 2. A yoke 22—22 projected from a hand grip 23 is attached to resilient elements 21 at approximate midpoint, as indicated at 24—24. The brackets 19 and 20 should be so placed that this midpoint lies approximately in a plane passing through the center of mass of the system (plane CP of Fig. 4) to avoid tilting of the system by any laterally applied force.

A flexible double electrical conductor 25 passes through the hand grip and is provided with a thumb switch 26. The connections from the switch to the motor may be as convenient and are not shown.

It is also desirable to provide units which are to be used on vertical surfaces with resilient supporting means such as the springs 27—27 which are attached to the motor in the plane of the

center of mass or, if preferred, in a plane passing through the axis of the motor shaft. The wires or cords extended from these springs may terminate in loops to be held in the hand of the operator or may be passed over an elevated pulley and provided with a counterweight by which the weight of the unit is balanced. The first named arrangement is adapted to units of the smallest size; the latter to large units.

In assemblies of larger size, such as are adapted to polishing and sanding floors and pavements, it may be desirable to modify the guiding element in the manner illustrated in Fig. 3. In this modification the yoke member 22 is attached to an arm 28 which is projected downwardly as at 29 and terminates in a foot piece 30, which may be covered with felt for use on floors or faced with metal or hardwood for use in sanding. A handle 31 is pivoted on the angle member as at 32. This arrangement prevents the operator from bearing down on the vibrating assembly and avoids danger of tilting.

The essential elements of the above structure and the manner in which it functions are illustrated in the diagram Fig. 4 in which only the outlines of the primary elements are shown.

The motor 10 is so mounted that the axis X of shaft 16 is normal to plane P of platen 12 and passes at least approximately through the center of the platen. The eccentric weights 17 and 18 have offsets F_1 and F_2 . The center of mass of the system is indicated at C and the plane parallel to plane P and passing through the center of mass is indicated at CP.

In operation, as the motor shaft rotates above the critical speed of the system, the two unbalanced weights generate a vibration about the axis X passing through the center of mass. For efficient polishing, the surface P should vibrate in its own plane. To produce this result, the rotating vectors F_1 and F_2 must be at least substantially and should be exactly in phase and must have equal moments about the center of gravity C of the vibrating system. Mathematically expressed, vector F_1 multiplied by arm A_1 must equal vector F_2 multiplied by arm A_2

$$(F_1 A_1 = F_2 A_2)$$

When this condition obtains (above the critical speed) we have a freely vibrating system with a circular path of vibration about an axis passing through the center of mass and in planes parallel to the plane of the platen and normal to the axis of rotation.

The amplitude of vibration bears no relation to the rotative speed of the motor, the radius of the orbit being proportional to the ratio of the sum of the rotating vectors F_1 and F_2 to the total mass of the vibrating system. Thus, in the force diagram Fig. 5, which illustrates actual values for a working hand polisher, vector $F_1=506$ centimeter grams, vector $F_2=1012$ cm. gr. and the resultant force F_3 effective at the center of mass is 1518 cm. gr. The arm A_1 is 10.2 cm. and the arm A_2 is 5.1 cm. As

$$506 \times 10.2 = 1012 \times 5.1$$

the force F_3 is applied in a plane normal to axis X. The actual weight of the vibrating sys-

tem is 3855 gr. and the radius of orbit is the ratio 1518 to 3855 or 0.4 cm. approximately. This unit is provided with a 110 volt A. C. motor rating $1/15$ H. P. and rotating 1800 R. P. M., and the diameter of platen 12 is about seven inches.

As all parts of the polishing surface carry the same weight and move at the same speed they are equally effective, a sharp contrast to the disc polishers in which only the outer portions of the disc move fast enough to be useful. Polishing with the described device is effected by rapid movement under light pressure, is very rapid, and there is little or no tendency to squeeze out the polishing or abrasive agent.

Because of the high vibratory speed and the light bearing on the surface to be treated, frictional resistance is reduced to the point at which it does not damp vibration and in any ordinary service need not be taken into account in calculating the radius of orbit or the relative values of $F \times A$. For the same reason there is substantially no resistance to movement of the device over horizontal surfaces, and the machine while in operation may be guided in all directions without appreciable effort.

I claim as my invention:

1. A device adapted to smoothing solid surfaces, comprising: a platen; a motor rigidly mounted on said platen with its shaft perpendicular thereto; a pair of eccentric weights attached to said shaft, rotating therewith and positioned on opposite sides of the center of mass of the system, said weights being at least substantially in phase and being so proportioned and positioned as to produce vibration of the system in planes parallel to the plane of said platen; a handle, and resilient means for attaching said handle to said motor on opposite sides thereof.

2. A device adapted to smoothing solid surfaces, comprising: a platen; a motor rigidly mounted on said platen with its shaft perpendicular thereto; a pair of eccentric weights attached to said shaft, rotating therewith and positioned on opposite sides of the center of mass of the system, said weights being at least substantially in phase and being so proportioned and positioned as to produce vibration of the system in planes parallel to the plane of said platen; a handle, and resilient means for attaching said handle to said motor on opposite sides thereof, said attachment being made in a plane passing substantially through said center of mass.

GOTTHOLD HARRY MEINZER.
